UNITED STATES PATENT OFFICE.

RAY A. THOMPSON, OF CHICAGO, ILLINOIS, ASSIGNOR TO ALUMOYD SIGN & SIGNAL CO.,
OF CHICAGO, ILLINOIS, A CORPORATION OF ILLINOIS.

SIGN.

Application filed September 22, 1926. Serial No. 137,017.

My invention relates to signs and is more particularly related to an improved sign adapted to be employed at street and highway junctions and intersections.

5 One object of the invention is to provide an improved means for connecting the sign portions to each other and to the supporting member therefor so that a rigid and strong connection with the minimum amount of material may be obtained.

10 Another object of the invention is to provide a novel means for reenforcing the sign plates.

15 More particularly it is an object of this invention to connect the projecting letters of the sign to the rim of the sign plate in such a manner as to use the material in the letters as a means for reinforcing the sign plate.

20 I will now describe one form which my invention may take by referring to the accompanying drawings. However, I wish it to be distinctly understood that I do not intend to limit myself to the exact details 25 shown and described, but that I intend to take advantage of all such modifications as would occur to one skilled in this art and as would fall within the scope of the claims.

In the drawings—

30 Fig. 1 is a side view of my improved sign construction;

Fig. 2 is a view partly in section taken along the line 2—2 of Fig. 1; and

35 Fig. 3 is a side view of a modified form of mounting for the sign.

Referring now in detail to the drawings, the numeral 5 indicates a post having a reduced top portion 6 upon which the cap 7 is fitted. This cap has an internal key member 8 for engagement of a portion of the top and a set screw 9 to prevent turning of the cap on the post. The upper portion 10 of the cap 7 is reduced in diameter and has a polygonal opening 11 extending therethrough. The sign plate 12 has a dependent mounting portion 13 substantially centrally of one edge thereof. This mounting portion 13 is provided with a series of faces adapted to engage the inner faces of the opening 11 and be secured therein by a set screw or other suitable securing means. The plate 12 is provided with a peripheral flange 14 extending therearound. In order to strengthen and brace the plate 12 adja-

cent the portion 13, transversely, extending 55 flanges 15 and 16 are provided. These flanges extend substantially to the outer edge of the portion 10 of the cap member and serve as a reinforcement for preventing the destruction of the sign by an impact in a 60 direction transversely thereof. Immediately above the portions 15 and 16 the plate 12 is thickened through a substantial distance on opposite sides thereof to give added 65 strength along the center portion of the sign.

The sign plate 12 has a thin central portion 18 from which the characters 20 project to form the legend thereon. These characters 20 in signs heretofore known, 70 have been spaced from the upper and lower edges of the sign plate or in some instances, instead of projecting from the plate, they have been cut out of the plate material. In both of these forms difficulty has been experienced in getting sufficient strength at the center portion of the plate. This weakness quite often results in the sign plate being broken at one side or other of the support which, of course, destroys the entire 80 sign legend. To overcome this weakness without adding materially to the amount of material in the sign plate, I have provided the integral ribs 19 which are of substantially the same thickness as the raised characters and which connect the upper and lower edges thereof with the upper and lower edges of the sign plate, thus utilizing 85 the material of the characters as a reinforcing and bracing portion for the sign plate. 90

In order to provide means for securing a second plate at an angle to the first name plate, I form on the upper edge of the plate 12 a supporting member 22 which is substantially of the same size as the portion 10 of the cap member 7 and which has a polygonal opening therein. This opening is engaged by a polygonally projecting member 23 secured to the bottom edge of the plate 24 and fitting tightly in the socket of the member 22. 95 The plate 24 is also provided with transversely projecting flanges 25 and 26 which are similar to the flanges 15 and 16 provided on the plate 12 and serve the same purpose of reinforcing the connection in a transverse direction. The plate 24 also has a thickened portion at 27 corresponding to the thickened portion 17 of the plate 12 and the raised 100 portion 18 of the plate 12.

characters 29 are connected with this thickened portion by the ribs 28 in substantially the same manner as the characters 20 are connected to the portion 17. A direction indicating ornament 20 may be provided on the top plate 24.

Referring now to Fig. 3, I show a bracket 31 which may be secured to a wall 32 and which has a supporting portion 33 extending upwardly therefrom adapted to receive the projecting portion of the plate 12 in substantially the same manner as the cap 7 receives the portion 13. This modification may be used in places where it is advisable to secure the sign to the corner of the wall or building.

From the above description, it is thought the advantages obtained by the particular manner of the reinforcement of the sign plates by utilizing material in the projecting characters will be clearly apparent. Signs of this character are now being made of aluminum alloys in order to provide a weather resisting material as well as to reduce the weight of the plates. It is a well known fact that these aluminum alloys have a comparatively low tensile strength and therefore, are easily broken by being struck or by having playful youngsters hanging on the end of the sign and the point of breaking is usually very close to the center or supporting portion of the sign. By providing the ribs 17, 19 and 21 which connect the sign characters with the laterally extending flanges of the sign plate, I am enabled to obtain a maximum reinforcement of the plates at their point of greatest strain with only the addition of a very small amount of material necessary to form the ribs 19.

Having thus described my invention, what I desire to claim and secure by U. S. Letters Patent is:

1. A sign plate having a reinforcing flange and a mounting portion substantially centrally of one side edge thereof, raised sign characters projecting from opposite sides of said plate cast integral therewith and projecting ribs of substantially the same thick-

ness as said characters connecting certain of said characters with said flange adjacent said mounting portion.

2. A sign plate having a reinforcing flange and a mounting portion on one side edge thereof, raised sign characters projecting from one side of said plate cast integral therewith, and projecting ribs rigidly and permanently connecting certain of said characters with said flange adjacent said mounting portion.

3. A sign structure comprising a sign plate having reinforcing ribs on opposite side edges thereof, mounting means on one side edge connected with the rib thereon, a supporting means for supporting a similar sign plate on the other side edge and connected with the rib thereon, raised sign characters projecting from opposite sides of said plate cast integral therewith and ribs rigidly and permanently connecting the upper and lower edges of said characters with said reinforcing ribs whereby the material in said characters and ribs braces said plate.

4. A sign structure comprising a sign plate having reinforcing ribs on opposite side edges thereof, mounting means on one side edge connected with the rib thereon, a supporting means for supporting a similar sign plate on the other side edge and connected with the rib thereon, raised sign characters projecting from said plate and ribs integrally connecting the upper and lower edges thereof with said reinforcing ribs, a second sign plate having mounting means engaging said supporting means, a reinforcing rib along the lower edge thereof and connected with said mounting means and sign characters projecting from said second plate having ribs of substantially the same thickness at said sign characters extending to and connected with the reinforcing rib thereon.

In witness whereof, I hereunto subscribe my name this 2nd day of September A. D., 1926.

RAY A. THOMPSON.
